(57) **CLAIM**

The ornamental design for a center pull-through dispenser,
as shown and described.

DESCRIPTION

FIG. 1 is a front elevation view of a center pull-through
dispenser incorporating my new design;

FIG. 2 is a rear elevation view thereof;

FIG. 3 is a left side elevation view thereof;

FIG. 4 is a right side elevation view thereof;

FIG. 5 is a top plan view thereof;

FIG. 5 is a top plan view thereof; and,

FIG. 6 is a perspective view from in front of, above, and the
right side thereof.

The broken lines in FIGS. 1-6 form no part of the claimed
design and include dot-dashed lines that define the bounds of
the claimed design and dashed lines that illustrate portions
of the center pull-through dispenser that form no part of the
claimed design.
